RATION OF NEW JERSEY.

FEED MECHANISM.

1,352,746.

Specification of Letters Patent. Patented Sept. 14, 1920.

Application filed December 14, 1916. Serial No. 136,935.

To all whom it may concern:

Be it known that I, FRED V. HART, a citizen of the United States, residing at Lynn, in the county of Essex and State of Massachusetts, have invented certain new and useful Improvements in Feed Mechanisms; and I do hereby declare the following to be a full, clear, and exact description of the invention, such as will enable others skilled 10 in the art to which it appertains to make and use the same.

This invention relates to mechanism for feeding a succession of articles or blanks from a magazine or supply-holder.

15 In feeding articles successively from a supply, it is sometimes necessary that certain of the articles, as fed, occupy positions, relative to the articles fed before and afterward, which are different from the relative 20 positions occupied by the articles in the magazine or supply-holder. This is particularly true in the case of wedge-shaped heel-lifts. Such lifts, owing to the fact that they taper from the rear edge to the front edge, 25 can not be stacked loosely in a magazine unless substantially half of the lifts be turned in a position opposite to that of the other lifts, so as to balance the thick edges of half of the lifts against the thin edges of 30 the other lifts. Accordingly, it has been proposed to stack such wedge-lifts in alternating positions, that is, with the thick edge of each lift adjacent the thin edge of the next lift in the stack. When lifts are fed 35 from such a stack, however, if it be desired that they all be fed in similar positions with respect to their thicker and thinner edges, as is necessary in feeding the lifts automatically to machines in which they are utilized 40 in the manufacture of heels, special provision is necessary for turning the lifts all to similar positions either after, or in connection with, the operation of feeding them.

The object of the present invention is to 45 produce a feed-mechanism, of simple construction and operation, by which articles may be fed successively and may, at the same time, be turned so as to bring them into a required relative position other than that 50 in which they are stacked and arranged in the magazine or supply-holder. More par-

ticularly, the object of the invention is to produce a mechanism by which wedge-shaped heel-lifts, stacked in alternating positions, may be fed, one by one, all in the same position with respect to their thicker 55 and thinner edges.

To the foregoing end, it is proposed to stack the heel-lifts, or other articles which are to be fed, in a suitable magazine, to feed 60 the articles one by one from the end of the stack, and to turn the articles, in their own planes, as an incident of the feeding operation, from one position to another, so that the position in which the articles are fed 65 is different from that in which they are stacked. In the preferred embodiment of the invention, the articles are turned while in the magazine, prior to their discharge therefrom, but the invention, as defined in 70 the claims, is of sufficient breadth to include turning the articles either before, after or during the discharge thereof.

A machine for feeding articles in the manner just set forth is illustrated in the accompanying drawings, in which Figure 1 is a plan-view of the machine; Fig. 2 is a side-elevation; and Fig. 3 is a partial section on the line 3—3 in Fig. 1, but on a slightly 75 larger scale.

The invention is illustrated as embodied in a machine adapted particularly for feeding wedge-shaped or tapering blanks, such as the wedge-lifts used in the manufacture of heels. The blanks are stacked in a magazine which comprises four parallel members, 80 4, 6, 8 and 10, having the form of angle-bars. These members are mounted, in vertical position, upon a horizontal turntable 12, and are fixed thereon by means of brackets 14 secured to the turntable by binding-screws. The screws project through elongated openings in the brackets, as shown in Fig. 1, so that upon loosening the screws 85 the magazine-members may be adjusted toward or from each other to accommodate blanks of different sizes.

The blanks are placed in the magazine with their lateral edges against the flanges 16 on the magazine members, and these 100 flanges are cut away at different levels, as shown in Fig. 2, in accordance with the di-

- rections in which the successive blanks are discharged from the magazine. The flanges on the members 6 and 10 are cut away high enough to permit the passage of the thicker edge of a blank, while the flanges on the members 4 and 8 are cut away only high enough to permit the passage of the thinner edge of a blank, and it will be apparent that with the blanks 30 arranged in alternating 5 positions, as shown in Fig. 2, this arrangement of the flanges is such that if the magazine be given a half-rotation, about its vertical axis, after the discharge of each blank from the bottom of the stack, the blanks, if 10 expelled from the magazine in the same direction, will all be discharged with their thick edges to the left, as shown in Figs. 1 and 2, and with their thinner edges to the right.
- 20 The turntable 12 is fixed on a vertical shaft 18, which is journaled in a sleeve 20 depending from an upper plate 22. This plate constitutes a part of the frame of the machine, and it is supported, in horizontal 25 position, by uprights 24 which connect it rigidly with a horizontal base-plate 26.
- The weight of the magazine and its contents, and of the turntable, is supported by a ball-bearing 28 inclosed within the sleeve 30 20. The turntable and the magazine are actuated by rotation of the shaft 18, and for this purpose a gear 32 is fixed to the lower end of the shaft. This gear coöperates with a mutilated pinion 34, which is 35 fixed on a power-shaft 36, journaled vertically in bearings on the frame-plates 22 and 26. The pinion 34 has the number of teeth necessary to turn the gear 32 through half of a rotation at each engagement, and the 40 pinion is rotated constantly by the power-shaft, this shaft being provided with a sprocket-wheel 38 which is connected, by a sprocket-chain 40, with any suitable source of power. Where the feed-mechanism 45 operates with an automatic machine for operating upon the articles fed, the chain is connected with the mechanism of such machine, so that the feed-mechanism may be actuated in timed coöperation therewith.
- 50 After each half-rotation of the shaft 18, its movement is arrested, and further rotation of the turntable is prevented, until the next engagement of the gears, by a spring-pressed detent 42 which slides into engagement with one or the other of two diametrically-arranged recesses in the turntable, as shown in Figs. 1 and 2.
- The blanks are expelled from the magazine by means of a plunger in the form of 55 a thin strip 44 of sheet-metal. This plunger is fixed, at one end, to a block 46 which slides toward and from the turntable in a guideway 48 formed in the frame-plate 22, and the amplitude of movement of the block 60 is such as to cause the end of the plunger

to engage the edge of the lowermost blank in the magazine and expel this blank from the magazine, the operative end of the plunger reaching the position shown in dot-and-dash lines in Fig. 1.

70

The feed-plunger 44 is actuated by a cam-mechanism operated in timed relation with the rotative movements of the turntable. For this purpose a cam 50 is fixed on the power-shaft 36, and this cam engages a 75 roller 52 on an arm 54 which projects integrally from a sleeve 56. This sleeve turns on a rod 58 fixed vertically in the frame-plates. A second arm 60, projecting integrally from the sleeve 56, is connected, by 80 a link 62, with an arm 64. The arm 64 is integral with a sleeve 66, which turns upon a second rod 68 fixed vertically in the frame-plates. A second arm 70, integral with the sleeve 66, is connected, by a short link 72, 85 with the slide-block 46.

75

When the projecting part of the cam 50 engages the roller 52, it acts, through the connections just described, to advance the slide-block and the feed-plunger, and since 90 the power-shaft moves in the direction of the arrow in Fig. 1, that is, counter-clockwise as shown in that figure, this movement of the feed-plunger occurs shortly after a half-rotation of the magazine and while the 95 latter is stationary.

90

The return-movement of the feed-plunger and its actuating mechanism is produced by a spring 76, of which one end is attached to the arm 54 while the other end is attached 100 to a pin 78, which is secured, for convenience, in the rod 68. After each return-movement of the feed-plunger, the mutilated pinion 34 again acts to impart a half-rotation to the magazine.

105

The feed-plunger acts with sufficient rapidity to eject each blank from the frame-plate 22, and the blank may then be received in a chute or conductor 77, of any suitable form, for conveying it, in the position in which it is discharged, to the machine (not shown) in which the blank is to be utilized.

110

While the invention has been particularly described as embodied in a machine for 115 feeding wedge-shaped heel-lifts or blanks of similar form, it will be apparent that it may be used in connection with articles of other forms and characters, wherever, in fact, it is necessary that the articles as fed 120 be turned to positions other than the relative positions which they occupy in the magazine or supply-holder. It will also be apparent that the invention is not limited to the details of construction and operation 125 of the illustrated embodiment thereof, but that it may be embodied in various other forms within the scope of the following claims.

120

The nature and scope of the present in- 130

vention having been indicated, and its preferred embodiment having been specifically described, what is claimed as new is:

1. Feed-mechanism having, in combination, a rotatable magazine for holding a stack of dissimilarly disposed tapering articles; means for removing articles successively from the end of the stack; and means for partially rotating the magazine between the removal of the successive articles in such manner that the removed articles are similarly disposed.

2. Feed-mechanism having, in combination, a magazine in which the articles to be fed may be stacked; means for expelling articles laterally, from the end of the stack, in succession; and means for imparting a half-rotation to the magazine after each operation of the expelling-means.

3. Feed-mechanism having, in combination, a magazine adapted to hold wedge-shaped blanks stacked with their thicker and thinner ends alternating; an expelling device movable transversely through the bottom of the magazine in a direction to engage the lowermost blank at one of its lateral edges and expel it from the magazine; and mechanism for reciprocating the expelling device, and for imparting successive half-rotations to the magazine timed to alternate with the operation of said device.

4. Feed-mechanism having, in combination, a rotatable holder for a stack of dissimilarly disposed tapering articles; means for successively engaging articles in the stack and removing them from the holder; and means for turning the holder, between successive removals, through a definite angle so as to control the angular positions in which the respective articles are removed.

5. Feed-mechanism, for delivering successive wedge-shaped heel-lifts having, in combination, means for holding a supply of such lifts stacked in alternate positions as to their thicker and thinner edges; and mechanism for removing lifts successively from the stack and for turning the lifts, as an incident of the feeding operation, substantially in the planes of their faces to bring them all, as fed, to the same position with respect to their thicker and thinner edges.

6. Mechanism for feeding wedge-shaped heel-lifts having, in combination, means for holding a stack of such lifts arranged with their thicker and thinner edges alternating, and means coöperating with said first-named means for removing the lifts successively from the stack, and for turning the lifts, substantially in the planes of their faces, to bring them all, as fed, to the same position with respect to their thinner and thicker edges.

7. Feed-mechanism having, in combination, a magazine for holding a stack of al-

ternately disposed tapering articles of sheet material; means for removing said articles from one end of the magazine; and means for partially rotating said articles in their own planes to bring them into similar positions.

8. Feed-mechanism having, in combination, a magazine for holding a stack of alternately disposed tapering articles of sheet material; means acting upon said articles for successively removing them therefrom; and means for turning said articles through 180 degrees in their own planes to cause them to be similarly disposed.

9. Feed-mechanism having, in combination, a magazine for holding to be fed a plurality of articles stacked in opposite relation with respect to certain characteristics; means for successively removing articles from one end of the stack while maintaining the articles in their original planes; and means for effecting intermittent relative half-rotations of said magazine and said removing means to similarly position the articles.

10. Feed-mechanism for delivering tapering articles having, in combination, a magazine for holding a plurality of said articles in alternately disposed face-to-face stacked relation; intermittently operated means for engaging successive articles at one end of the stack and removing them therefrom; and means acting during periods of rest of said removing means for imparting successive half-rotations to said magazine.

11. Feed-mechanism for delivering articles having, in combination, a holder for a stack of dissimilarly disposed tapering articles; means for removing articles successively from said holder; and means for effecting definite rotative movements of said articles about their substantially central axes and in their own planes for similarly positioning the respective articles removed.

12. Feed-mechanism for delivering uniformly tapering articles having, in combination, means for holding to be fed a plurality of said articles in alternately disposed stacked relation; means acting upon the several articles for giving them a partial rotation in their own planes and about their substantially central axes and for transferring them successively from said holding means to a receiving point where they occupy similar positions with respect to their tapers.

13. Feed-mechanism having, in combination, a rotatable member; a magazine associated therewith for holding a stack of dissimilarly disposed articles to be fed; means for intermittently rotating said member through definite angles corresponding to the relative positions of the articles in the stack; means for restraining said ro-

- tatable member and its associated magazine in position; and means acting upon the successive articles at one end of the magazine during periods of rest of said rotatable member and magazine for removing said articles from said magazine in similar positions.
14. Feed mechanism for delivering tapering heel lifts of sheet material having, in combination, a magazine for holding a stack of such lifts disposed alternately and in face-to-face relation; means for intermittently rotating said magazine through 180 degrees to bring the endmost lifts in the stack into similar positions; and means for removing the endmost lifts so positioned successively.
15. Feed mechanism for delivering tapering heel lifts of sheet material having, in combination, a magazine for holding a stack of such lifts disposed alternately and in face-to-face relation; means intermittently rotating said magazine through 180 degrees to bring the endmost lifts in the stack into similar positions; and reciprocating means for engaging one of the tapering side edges of each successive endmost lift and ejecting it from the magazine.
16. Feed-mechanism for delivering tapering articles having, in combination, a rotatable holder for a stack of said articles disposed in opposite relation, means normally disposed adjacent said holder and adapted to be projected through the lower end thereof to successively remove the articles therefrom, and means for turning the holder, between successive removals, through a definite angle so as to control the angular positions in which the respective articles are removed.
17. Feed - mechanism for delivering tapering articles having, in combination, a rotatable holder for a stack of said articles disposed in opposite relation, a stationary support adjacent said holder and in the plane of the bottom wall thereof, means for intermittently rotating said holder, means acting during periods of rest of said holder for pushing the lowermost article from the holder and upon said support, and means for guiding and maintaining control of said article as it is pushed upon said support.
18. Feed mechanism having, in combination, a wedge lift holder adapted to contain wedge lifts stacked in oppositely disposed relation, supporting means upon which lifts are deposited, means for successively transferring lifts from said holder to said supporting means, and means for causing said lifts to occupy similar positions upon said supporting means.
19. Feed mechanism having, in combination, a holder for blanks arranged in a stack in alternate relation, and means acting on the successive blanks in said holder for transferring them to a point of delivery, said holder and said transferring mechanism being relatively rotatable in the plane of the blanks to cause the delivered blanks to occupy similar positions.
20. Feed mechanism having, in combination, supporting means upon which heel lifts are deposited, a holder for lifts arranged in a stack with their breast edges facing alternately in opposite directions, and means for transferring the lifts successively from the stack to said supporting means, said holder and said transferring means being relatively rotatable in the plane of the lifts to cause the lifts to be deposited upon said supporting means in similar positions with respect to their breast edges.
21. Feed mechanism for tapering articles of sheet material having, in combination, means for holding a stack of such articles with their thick and thin ends alternating, means for transferring the articles successively from the stack to a point of delivery, and means for effecting relative rotatable movements of the holding means and the transferring means in the plane of the articles to cause the articles to be delivered in similar positions with respect to their thick and thin ends.

FRED V. HART.
